UNITED STATES PATENT OFFICE.

HAROLD D. PENNEY, OF PELHAM, NEW YORK, ASSIGNOR TO THE ST. MUNGO MANUFACTURING COMPANY OF AMERICA, OF NEWARK, NEW JERSEY.

DESIGN FOR A GOLF-BALL.

44,109.

Specification for Design.

Patented May 27, 1913.

Application filed December 21, 1911. Serial No. 667,247. Term of patent 7 years.

To all whom it may concern:

Be it known that I, HAROLD D. PENNEY, a citizen of the United States, residing at Pelham, in the county of New York and State of New York, have invented a new, original, and ornamental Design for a Golf-Ball, of which the following is a specification, reference being had to the accompanying drawings, forming a part thereof.

Figure 1 is a plan view of the golf ball.

Fig. 2 is another view of the ball rotated 90 degrees on the axis A—A in the direction of the arrow 1.

I claim:

The ornamental design for a golf ball as shown.

HAROLD D. PENNEY.
